(57) **CLAIM**

The ornamental design for a toy gun as shown and described.

DESCRIPTION

FIG. 1 is a perspective view of a toy gun showing my new design;

FIG. 2 is a front view thereof;

FIG. 3 is a rear view thereof;

FIG. 4 is a left view thereof;

FIG. 5 is a right view thereof;

FIG. 6 is a top view thereof;

FIG. 7 is a bottom view thereof;

FIG. 8 is a front perspective view thereof; and

FIG. 9 is a rear perspective view thereof.

FIG. 10 is an enlarged view of portion 10 identified in FIG. 5; and,

FIG. 11 is an enlarged view of portion 11 identified in FIG. 9.

The broken lines shown in the drawings represent portions of the article that form no part of the claimed design.

1 Claim, 9 Drawing Sheets
